UNITED STATES PATENT OFFICE.

THOMAS F. HAGERTY, OF SAN FRANCISCO, CALIFORNIA, ASSIGNOR TO
WILLIAM E. HOYT, OF NEW YORK, N. Y.

SAD-IRON.

SPECIFICATION forming part of Letters Patent No. 556,537, dated March 17, 1896.

Application filed December 19, 1895. Serial No. 572,646. (No model.)

To all whom it may concern:

Be it known that I, THOMAS F. HAGERTY, a citizen of the United States, residing at San Francisco, in the county of San Francisco and 5 State of California, have invented certain new and useful Improvements in Sad-Irons; and I do hereby declare the following to be a full, clear, and exact description of the invention, such as will enable others skilled in the art 10 to which it appertains to make and use the same.

My invention relates to improvements in sad-irons; and one object of my invention is the provision of a sad-iron which will embody 15 within itself a chamber which will diffuse the heat properly to the iron, which will remain heated for a long period.

Another object of my invention is the provision of a self-heating sad-iron which will 20 embody a fluting device which will not render the iron cumbersome or inconvenient to handle and which fluting device will be thoroughly practical.

Another object of my invention is the provision of a sad-iron which will be thoroughly 25 efficient and practical and which can be produced at a moderate cost.

To attain the desired objects the invention consists of a sad-iron embodying novel features of construction and combination of 30 parts, substantially as disclosed herein.

Figure 1 represents a perspective view of my sad-iron. Fig. 2 represents a vertical longitudinal sectional view thereof. Fig. 3 represents a side view of the iron with the stationary fluting-plate applied. Fig. 4 represents a perspective view of the fluting devices in operative positions to clearly show the manner of using for fluting; and Fig. 5 represents 40 a transverse sectional view of the sad-iron, taken in line $\alpha\alpha$ of Fig. 2.

Referring by numbers to the drawings, the numeral 1 designates the body of the iron, which is of usual shape or form and is made 45 hollow to form a chamber 2, having at one end the guides formed by a single outer flange 3 at each side, against which is fitted and slides the door or gate 4, having the handle 5 and the air-supply openings 6 near the upper edge thereof. The chamber is also supplied or provided with the base-flue 7 for the

supply of air at the base, which base-flue 7 extends from near the end to about the center thereof, and upon the base-flue and the bottom of the chamber is placed the fuel to 55 be burned to heat the body of the iron. The door in its lower position fits between the outer end of the base-flue and the flanges 3 at the end of the iron. From this construction it will be seen that the door can be raised 60 until it clears the outer end of the base-flue and tilted inward to rest upon said flue, as clearly shown, and in this position the air will be fed through the base-flue to the fuel, and after the fuel has been properly kindled 65 the door can be dropped into place by simply tilting the iron and causing the door to fall and drop against the guides formed by the flanges 3 and then drop into its lower position between the end of the base-flue and the 70 flanges 3 at the end of the iron.

The side walls of the iron are provided with vertical feed ducts or passages 8, which lead from the top of the iron to and under the fire which is upon the base-flue and bottom of 75 the iron, and by this means the air is supplied from the top down under the fire, and the hollow top 9 has the chimney 10, for permitting the escape of the products of combustion, and the top is provided with the 80 curved portion 11, forming uprights 12, to which the handle 13 is secured by means of the rod or bolt 13^X, as clearly shown in Fig. 2. From this construction it will be understood that when it is desired to use the iron, 85 a sufficient quantity of the fuel is placed upon the base-flue and bottom of the chamber of the iron and the door is raised above the outer end of the base-flue and tilted inward to rest upon the flue, and after the material 90 has been ignited it will be seen that the air is fed to the fuel through the side ducts or flues and through the base-flue, causing a quick combustion, and after the fire has been sufficiently started or kindled the door is released from the end of the flue by tilting the iron and falls between the outer end of the base-flue and the flanges 3, and the fire is then supplied with air by the side flues.

I provide in connection with my iron fluting devices, which consist of the separate handle 14, to which is connected the curved

fluting-plate 14^x, which operates in connection with the fluting-plate 15, which plate 15 is secured to the side of the iron.

It is evident that I provide a self-heating sad-iron which is thoroughly efficient and which by the further reason of its combination of a fluting attachment is particularly desirable and will commend the article to all in need of such a device.

10 I claim—

The herein-described sad-iron having the hollow body or chamber, the side air-feeding ducts or flues leading from the upper portion of the body to the base thereof, the base-flue

extending from near one end of the chamber 15 to about the center thereof, the sliding or movable door or gate in one end of the iron adapted to be tilted inward to rest upon the base-flue, to allow the air to be fed through the base-flue as well as the side flues, and the hollow top for carrying off the products of combustion.

In testimony whereof I affix my signature in presence of two witnesses.

THOMAS F. HAGERTY.
